ASH TRAY OR SIMILAR ARTICLE

Frank J. Curran, 3250 S. Highland Ave.,
Downers Grove, Ill. 60515

Filed May 20, 1971, Ser. No. 145,592

Term of patent 14 years

Int. Cl. D27—03

U.S. Cl. D85—2 H

FIG. 1 is a perspective view of an ash tray or similar article, showing my new design;

FIG. 2 is a top plan view;

FIG. 3 is a side elevational view, the opposite side being substantially a mirror image thereof;

FIG. 4 is a cross sectional view taken on line 4—4 in FIG. 2; and

FIG. 5 is a bottom plan view thereof.

I claim:

The ornamental design for an ash tray or similar article, substantially as shown and described.
